UNITED STATES PATENT OFFICE.

PETER MALACZYNISKI, OF BROOKLYN, NEW YORK.

PADLOCK.

1,336,309.

Specification of Letters Patent.

Patented Apr. 6, 1920.

Application filed September 23, 1919. Serial No. 325,734.

To all whom it may concern:

Be it known that I, PETER MALACZYNISKI, a citizen of Poland, and a resident of the city of New York, borough of Brooklyn, in the county of Kings and State of New York, have invented a new and useful Padlock, of which the following is a full, clear, and exact description.

This invention relates to locks and particularly to an improved combination padlock and has for an object to provide a construction which is extremely simple, but which requires a very accurate adjustment of the parts to produce an unlocking operation.

Another object of the invention is to provide a combination padlock wherein means are provided which require two separate adjustments to completely lock or unlock the device.

In the accompanying drawings:

Figure 1 is a side view of a padlock embodying the invention, certain features being removed for illustrating certain of the details of construction.

Fig. 2 is an edge view of the structure shown in Fig. 1.

Fig. 3 is a sectional view approximately on line 3—3 of Fig. 2.

Fig. 4 is a sectional view through Fig. 3 on line 4—4.

Fig. 5 is a top plan view of the complete lock.

Fig. 6 is a sectional view through Fig. 3 on line 6—6.

Fig. 7 is a fragmentary sectional view similar to Fig. 3, but showing the parts in a different position.

Fig. 8 is an elevation and section through one of the locking rings or keepers embodying certain features of the invention.

Fig. 9 is an elevation and section through a second locking ring embodying certain features of the invention.

Fig. 10 discloses an elevation and two end views of a locking cam embodying certain features of the invention.

Referring to the accompanying drawings by numerals 1 indicates what may be termed a casing connected with a cross bar 2 by tubular member 3 which is provided with

shoulders at each end as shown in Fig. 3 and is held in place by the respective pins 4 and 5 secured to the member 3 by rivets or otherwise as may be desired. Pin 4 has a disk 6 rigidly secured thereto provided with letters, numbers or other indications with suitable graduations co-acting with one or more marks 7 on bar 2. Pin 5 extends through a cam disk 8 and is rigidly secured thereto, the extreme end, however, being journaled in the casing 1 as shown at the bottom of Fig. 3. This cam as shown in Fig. 10 is round and is provided with raised portions 9 and 10 on each face and depressions 11 and 12 on each face whereby the arms 13 and 14 and also the arms 15 and 16 which overlap the disk may be separated or allowed to approach according to the position of the cam. These arms are pivotally connected together in pairs at 17 and 18 and merge into pairs of locking bars 19 and locking bars 20. Each of the locking bars is provided with a number of notches 21 having a lug or projection 22 adjacent each notch so as to overlap the respective flanges 23 of the locking rings or keepers 24 and 25. These rings, as shown in Figs. 8 and 9, are provided with inwardly extending flanges 23, each flange having a pair of oppositely positioned notches 26 and an extra deep notch 27. The ring 24 has a flange adjacent one face while the flange 23 of ring 25 is set in a short distance so as to accommodate the first lug 28 of the shackle 29. A spring 30 is positioned between each pair of bars 19 so as to give the same a continuous tendency to open or spread to the position shown in Fig. 7 whereby they will interlock with the flanges 23 and move away from the various lugs 28 on the shackle extension 29'. The lugs 28 are something of the nature of buttress threads, so as to provide shoulders designed to interlock not only with the flanges 23 but with the hook-shaped members 31 on the respective locking bars 19. When the locking bars are in their locked position they appear as shown in Fig. 3, and when in their unlocked position as shown in Fig. 7. When the various locking rings or keepers 24 or 25 are in their unlocked position they assume the position shown

in Fig. 6 with all of the notches 27 in line as well as notches 26. If the notches 26 were not provided the bars 19 could not be moved to their open position as shown in 5 Fig. 7. By reason of this construction and arrangement the various locking rings 24 and 25 must be alined on both legs of the shackle 29 and then the disk 6 turned until the cam disk 8 is in the position shown in 10 Fig. 7 whereupon the springs 30 will cause the bars 19 to move over into the notches 26. This will free the shackle extension 29 from engagement with any of the locking members and consequently the shackle may be 15 removed by a direct pull thereon. To strengthen and stiffen the parts and also to cause a proper operation of the various parts the casing 1 is provided with a pair of tubular upstanding members 32 as indicated in 20 Figs. 3, 4 and 6, said tubular upstanding members being provided with slots 33, 34 and 35 for accommodating the locking bars 19 and the shackle extension 29' with their lugs 28.

25 It will be noted that the indications on the disk 6 in respect to the line 7 on bar 2 cannot be changed to vary the combination unless the lock is taken to pieces and the cam disk 8 shifted. However, the combination 30 of the locking rings or keepers 24 may be varied easily. As shown in Fig. 1 it will be seen that the locking ring 25 is provided with a number of letters arranged between vertical lines 36, each letter having an indication line 37 therebetween. This same arrangement is provided on the locking rings 24, but with a different arrangement of letters. When the various lines 37 of the proper letters are brought into alinement and also 35 into alinement with the indicating line 38 on casing 1 the notches 27 are all in line so that the disk 6 may be turned and the shackle 29 removed. If it is desired to change the combination of these locking 40 rings it will be necessary to remove the shackle 29, disk 6 and bar 2 and then rearrange the rings 24 as desired after which the bar 2 and disk 6 must be replaced. It will be noted that both legs of the shackle 29 45 are formed with locking means, the same being identical, but the rings 24 and 25 are duplicated on both sides, but preferably a different set of letters are used on the respective sides so that there will really be three 50 combinations, one for each side and one for the disk 6.

What I claim is:

1. A combination padlock comprising a casing, a shackle having a pair of locking 60 extensions projecting into part of the casing, a plurality of locking rings for locking said extensions, each of said rings being rotatable so as to be moved into and out of adjustment for locking and unlocking the 65 extension, a pair of auxiliary locking bars

for each of said extensions, and manually operated means for shifting said bars when the locking rings are alined in an unlocked position.

2. A combination lock in the form of a 70 padlock comprising a casing, a U-shaped shackle having a pair of locking extensions provided with shouldered members, a plurality of rings surrounding each of said extensions formed with notches for accommodating 75 the extensions so that the shackle may be applied and removed when the rings are positioned with the notches in alinement, each of said rings being formed with a flange for overlapping said notches when 80 the notches are out of alinement, and locking bars operated independently of the rings adapted to engage said locking extensions.

3. A combination lock of the padlock type comprising a casing having a pair of tubular 85 upstanding members, each upstanding member being formed with three slots, a U-shaped shackle having locking extensions fitting loosely in said upstanding members, said locking extensions having shouldered 90 projections extending through one of said slots in each of the upstanding members, a plurality of locking rings or keepers surrounding each of said upstanding members, each of said rings being formed with an internal flange having a notch for accommodating the projections from said locking extensions when the notches are in alinement, said internal flanges overlapping said projections when the notch in any of the locking 95 rings is out of alinement, a locking bar arranged in each of two of said slots, and means for causing said bars to interlock with said locking extensions.

4. A combination lock in the nature of a 105 padlock comprising a casing having a pair of spaced tubular members, each of said tubular members being formed with a pair of opposite slots and a third slot arranged between the two first mentioned slots, a shackle 110 having locking extensions fitting into said tubular members, each of said locking extensions being provided with a pair of shouldered portions extending toward the first mentioned slots and a third shouldered 115 portion extending toward the second mentioned slot, locking rings positioned to interlock with the last mentioned shouldered portion, a pair of locking bars having projections adapted to interlock with the first 120 mentioned projections on the locking extensions on the shackle, a cam for moving said locking bars into and out of engagement, and an operating member connected with said cam positioned exteriorly of the casing. 125

5. A combination lock in the form of a padlock provided with a casing, a pair of spaced tubular members, each member being provided with oppositely arranged slots, a U-shaped shackle having locking projections 130

extending into the tubular members, a pair of pivotally mounted locking bars for each of said tubular members operating in the slots therein, each of said tubular members being formed with a locking projection adapted to interlock with the projections on the locking extensions on the shackle, a

spring for moving said locking bars to an unlocked position, a rotatable cam for moving said locking bars to a locked position, 10 and an operating member extending to the exterior of the casing for operating said cam.

PETER MALACZYNISKI.
